(57) **CLAIM**

The ornamental design for a volatile actives dispenser, as shown and described.

DESCRIPTION

FIG. 1 is a front perspective view from above and to one side of the volatile actives dispenser showing the new design.

FIG. 2 is a front view of the volatile actives dispenser of FIG. 1.

FIG. 3 is a back view of the volatile actives dispenser of FIG. 1.

FIG. 4 is a top plan view of the volatile actives dispenser of FIG. 1, the bottom view being a mirror image thereof; and, FIG. 5 is a right side view plan view of the volatile actives dispenser of FIG. 1, the left side view being a mirror image thereof.

The broken line showing in FIGS. 1, 3, 4 and 5 is for illustrative purposes only and forms no part of the claimed design.
